14 Claims. (Cl. 196—18)

1

This invention relates to an improvement in the operation of solvent dewaxing petroleum hydrocarbons and, more particularly, is directed to preventing the formation and adherence of hard ice on the interior surfaces of chillers conventionally employed in said operation.

Petroleum fractions of the nature of distillates and residues and mixtures thereof containing waxy materials are normally treated to remove the wax therefrom by adding to the waxy oil a diluent material, chilling the mixture to a temperature at which the wax or a substantial portion thereof is precipitated and thereafter filtering, centrifuging or otherwise physically separating the wax from the oil. Those methods in which the diluent used is one tending to exert a preferential solvent action for oil over waxy material at low temperatures are commonly known as solvent dewaxing methods.

One widely used method of chilling the blend of waxy oil and solvent to the desired low temperature is by passing the same through a double pipe chiller of the Carbondale type. This machine consists of a number of pipes in series, each jacketed by an outer pipe of larger diameter. A cooling medium, such as brine solution or the like, is circulated between the two pipes, thus chilling the surface of the inner pipe through which the blend of waxy oil and solvent is passed. Inside of each of the inner pipes is a screw-like scraper composed of a central shaft with a helical scraper blade attached thereto. The scraper is revolved during the chilling operation, the blade thereof touching the inner surface of the pipe, removing adhering solid matter therefrom and forcing congealed wax along and out of the pipe as a slurry in the diluted oil.

It has been heretofore noted in solvent dewaxing operations employing a chiller of the type described that a small amount of water contained in the oil to be treated and/or dissolved in the dewaxing solvent used, is deposited as a hard ice formation on the cooled surface of the inner pipe in the chiller, leading to plugging of said chiller, breakage of the blades of the revolving scraper and acting as a partial insulator tending to inhibit further cooling of the oil contained in the pipe. This problem is of particular importance when the oil to be treated has a relatively high proportion of water dissolved therein or when the dewaxing solvent or solvent mixture employed has the tendency to dissolve water. In practice, it is necessary to recover the solvents employed for further use in treating fresh oil-wax mixtures. A customary method of re-

2

covering solvent from the dewaxed oil is by steam distillation of the oil-solvent mixture which tends to leave a certain amount of water incorporated in the solvent. Further use of such recovered solvents leads to the deposition of hard ice crystals in the chilling operation, giving rise to the aforesaid difficulties.

One method of overcoming the problem is to remove water from the oil and/or solvent employed. This method, however, has not been employed to any great extent due primarily to the expense of the operation involved. In some instances, a drying agent has been used, such as concentrated sodium carbonate solution, for drying the solvents prior to use or recovered from the oil and wax fractions by distillation. In practice, this procedure has consisted of contacting the solvent containing a small quantity of water with the solution of drying agent until the drying agent is so diluted that no further water is absorbed from the solvent. A portion of the diluted solution is then discarded and fresh concentrated solution is added to the remainder to maintain the absorption capacity of the drying agent at the proper level. In discarding a portion of the diluted solution, not only is some of the drying agent lost, but an appreciable quantity of solvent is lost, since such diluted solution is saturated with solvent at the treating temperature.

It is an object of the present invention to overcome the above mentioned difficulties in the chilling operation of solvent dewaxing by preventing the formation of a hard adherent ice to the walls of the chiller. A more specific object is to prevent the breakage of chiller scraper blades due to contact with said hard ice forming on the surfaces of the inner pipe of double pipe chillers conventionally employed in the art, for example, the Carbondale chiller. A further object is to prevent the plugging of chiller pipes. A still further object is to inhibit the formation of an ice coating on the chiller pipes, which tends to decrease the chilling effect of the surrounding cooling medium, acting as a partial insulator against the same. A very important object is the use of a dewaxing solvent in which small quantities of water may be tolerated without leading to the hard ice formation heretofore encountered in the chilling operation.

These and other objects which will be recognized by those skilled in the art are realized in accordance with the present invention. It has now been found that the formation of hard ice in the dewaxing chiller can be substantially inhibited by the incorporation of a small quantity

of a water miscible, oil immiscible organic acid or alcohol in the dewaxing solvent containing a minor proportion of aqueous contaminant. The resulting mixture of solvent containing small quantities of the order of from about 0.02 to about 0.8 per cent by weight of a water miscible, oil immiscible alcohol or organic acid even at the lowest chilling temperatures employed in dewaxing operations was found to inhibit the formation of a solid ice having a tendency to adhere to the surface walls of the chiller.

On the other hand, a soft or mushy non-adherent ice tends to form, which readily moves through the chiller pipes along with the waxy fraction being treated. The plugging of the chiller pipes due to hard ice formation therein, with resultant chipping and breaking of the chiller scrapers, is thus overcome.

The amount of alcohol or organic acid to be incorporated in the dewaxing solvent will be dependent upon the temperature at which chilling is carried out, upon the amount of water contained in the solvent or in the oil to be treated and upon the nature of the alcohol or acid employed. The present invention has been found to be particularly useful in solvent mixtures which have a relatively high tendency to dissolve water, such as those containing ketones. Hence, the incorporation of small amounts of water miscible, oil immiscible organic acids and alcohols has been found to be suitable for the ketone-benzol dewaxing solvents, such as mixtures containing 25 to 40 per cent acetone or methyl ethyl ketone, 12 to 25 per cent toluol and 40 to 60 per cent benzol conventionally employed in dewaxing.

The particular ratio of solvents to be used will be largely dependent on the characteristics of the oil under treatment. In general, a larger proportion of benzol or toluol necessitates the use of lower chilling temperatures to obtain an oil of a given pour test. In practice, the oil to be dewaxed is diluted with 3 to 4 volumes of the solvent mixture, chilled to a temperature at which the waxy constituents precipitate, generally to about 5° F. below the desired pour point of the oil and usually not lower than about -35° F. The precipitated waxy constituents are then separated from the dewaxed oil by filtration.

As those in the art know, blended dewaxing solvents are composed of a mixture of a solvent, for example, benzol or toluol, and an anti-solvent, such as methyl ethyl ketone or acetone. The alcohols and organic acids to be used in the present invention for inhibiting hard ice formation are of the anti-solvent type. For this reason it is possible to incorporate a fairly large volume of these additives in the dewaxing mixture provided a suitable adjustment is made in the solvent to anti-solvent ratio. Thus, by reducing the percentage of acetone or methyl ethyl ketone contained in the conventional benzol-ketone solvent mixture, a relatively large amount of alcohol or organic acid may be added. The final mixture so obtained is hence characterized by the absence of hard ice formation at the low temperatures employed without impairing its dewaxing properties. While the maximum amount of ice modifying agent which may be incorporated in the dewaxing solvent will be dependent on the particular nature of the alcohol or organic acid employed and with the ability of the final mixture to absorb the modifying agents, in general, an amount up to about 0.8 per cent by weight of the solvent may be effectively added to the solvent

without substantially affecting the dewaxing efficiency thereof. The lower limit of alcohol or acid to be used will largely depend on the amount of aqueous contaminant contained in the solvent. Accordingly, a sufficient proportion of alcohol or organic acid is contemplated to prevent the formation of a hard ice in the dewaxing process.

The alcohols or organic acids to be used in the present invention are water miscible, oil immiscible and include monohydric aliphatic alcohols, preferably those having less than four carbon atoms, such as methyl, ethyl, propyl, isopropyl alcohol; dihydric alcohols, such as ethylene glycol; trihydric alcohols, such as glycerol; fatty acids, preferably those having less than four carbon atoms, such as acetic and propionic acids. The above list is not intended to be restrictive and other water soluble alcohols and organic acids which will occur to those skilled in the art may likewise be used. However, as a practical matter, the less expensive and more easily available members of this group of compounds will generally be employed.

Having described in a general way the nature of this invention, it may be more readily understood by the following specific example.

A mixture of dewaxing solvent consisting of about 40 per cent methyl ethyl ketone, about 40 per cent benzol and about 20 per cent toluol and having a small amount of water present in about 1.0 per cent by weight based on the weight of solvent, and an oil to be dewaxed were chilled by flowing through a cooled pipe, employing a chilling temperature of -20° F. A hard ice formed under these conditions, preventing further flow of the liquid mixture.

A second sample of the above mixture of oil to be dewaxed, solvent and water having incorporated therein about 0.2 per cent by weight of methyl alcohol based on the weight of solvent, was treated under the same conditions and in this instance a mushy, soft, non-adherent ice formed which flowed along through the chiller tube with the waxy oil under treatment without interfering with the dewaxing efficiency of the solvent employed.

A third sample of the above mixture of oil to be dewaxed, solvent and water having incorporated therein 0.05 per cent by weight of ethyl alcohol based on the weight of solvent, was treated under the same conditions. This minor proportion of alcohol was sufficient to modify the appearance of ice crystals. When the amount of alcohol was increased to 0.6 per cent by weight of the solvent mixture, ice formation was completely eliminated at a temperature of -20° F.

Thus, the above experiments clearly show that the incorporation of a minor proportion of a water miscible, oil immiscible alcohol or organic acid in a dewaxing solvent, particularly the benzol-ketone mixtures conventionally employed, gives rise to an improved dewaxing solvent which in operation leads to formation of a soft, mushy, non-adherent ice. Hard ice crystal formation is thus substantially inhibited, leading to an improved flow rate of the liquid mixture through the chiller tubes, preventing the expensive and troublesome breakage of chiller scrapers and eliminating pre-treatment of solvents with drying agents to remove water therefrom, as has heretofore been necessary.

We claim:

1. In the method of dewaxing a petroleum hydrocarbon, comprising blending said hydrocarbon with a dewaxing solvent consisting of from about

25 to about 40 per cent acetone, from about 12 to about 25 per cent toluol and from about 40 to about 60 per cent benzol, and passing the resultant mixture through a chiller to precipitate wax therefrom, the improvement which comprises the addition to said solvent, prior to said passing, of a compound selected from the group consisting of water miscible, oil immiscible alcohols and organic acids in an amount less than about 0.8 per cent by weight of said solvent but sufficient to inhibit the formation of a hard, adherent ice on the inner surfaces of said chiller due to the freezing of water contained in the mixture under treatment.

2. In the method of dewaxing a petroleum hydrocarbon, comprising blending said hydrocarbon with a dewaxing solvent consisting of from about 25 to about 40 per cent methyl ethyl ketone, from about 12 to about 25 per cent toluol and from about 40 to about 60 per cent benzol, and passing the resultant mixture through a chiller to precipitate wax therefrom, the improvement which comprises the addition to said solvent, prior to said passing, of a compound selected from the group consisting of water miscible, oil immiscible alcohols and organic acids in an amount less than about 0.8 per cent by weight of said solvent but sufficient to inhibit the formation of a hard, adherent ice on the inner surfaces of said chiller due to the freezing of water contained in the mixture under treatment.

3. A dewaxing solvent consisting of benzol, toluol, and a low boiling aliphatic ketone in such proportion that a selective action is exerted as between wax and oil at reduced temperature and having incorporated therein a minor proportion of a compound selected from the group consisting of water miscible, oil immiscible alcohols and organic acids in an amount less than about 0.8 per cent by weight of said solvent but sufficient to inhibit hard, adherent ice formation during the dewaxing operation.

4. A dewaxing solvent consisting of from about 25 to about 40 per cent of a ketone selected from the group consisting of acetone and methyl ethyl ketone, from about 12 to about 25 per cent toluol, from about 40 to about 60 per cent benzol, and having incorporated therein from about 0.02 to about 0.8 per cent by weight of said solvent mixture of a compound selected from the group consisting of water miscible, oil immiscible alcohols and organic acids.

5. A dewaxing solvent consisting of benzol, toluol, and methyl ethyl ketone in such proportion that a selective action is exerted as between wax and oil at reduced temperature and having incorporated therein a minor proportion of a compound selected from the group consisting of water-miscible, oil-immiscible alcohols and organic acids in an amount less than about 0.8 per cent by weight of said solvent but sufficient to inhibit hard, adherent ice formation during the dewaxing operation.

6. A dewaxing solvent consisting of benzol, toluol, and acetone in such proportion that a selective action is exerted as between wax and oil at reduced temperature and having incorporated therein a minor proportion of a compound selected from the group consisting of water-miscible, oil-immiscible alcohols and organic acids in an amount less than about 0.8 per cent by weight of said solvent but sufficient to inhibit hard, adherent ice formation during the dewaxing operation.

7. In the method of dewaxing a petroleum hy-

drocarbon, comprising blending said hydrocarbon with a dewaxing solvent consisting of benzol, toluol, and a low boiling aliphatic ketone in such proportion that a selective action is exerted as between wax and oil at reduced temperature and passing the resultant mixture through a chiller to precipitate wax therefrom, the improvement which comprises the addition to said solvent, prior to said passing, of an aliphatic alcohol having less than 4 carbon atoms, in an amount less than about 0.8 per cent by weight of said solvent but sufficient to inhibit the formation of a hard, adherent ice on the inner surfaces of said chiller due to the freezing of water contained in the mixture under treatment.

8. In the method of dewaxing a petroleum hydrocarbon, comprising blending said hydrocarbon with a dewaxing solvent consisting of benzol, toluol, and a low boiling aliphatic ketone in such proportion that a selective action is exerted as between wax and oil at reduced temperature and passing the resultant mixture through a chiller to precipitate wax therefrom, the improvement which comprises the addition to said solvent, prior to said passing, of methanol, in an amount less than about 0.8 per cent by weight of said solvent but sufficient to inhibit the formation of a hard, adherent ice on the inner surfaces of said chiller due to the freezing of water contained in the mixture under treatment.

9. In the method of dewaxing a petroleum hydrocarbon, comprising blending said hydrocarbon with a dewaxing solvent consisting of benzol, toluol, and a low boiling aliphatic ketone in such proportion that a selective action is exerted as between wax and oil at reduced temperature and passing the resultant mixture through a chiller to precipitate wax therefrom, the improvement which comprises the addition to said solvent, prior to said passing, of glycerine, in an amount less than about 0.8 per cent by weight of said solvent but sufficient to inhibit the formation of a hard, adherent ice on the inner surfaces of said chiller due to the freezing of water contained in the mixture under treatment.

10. In the method of dewaxing a petroleum hydrocarbon, comprising blending said hydrocarbon with a dewaxing solvent consisting of benzol, toluol, and a low boiling aliphatic ketone in such proportion that a selective action is exerted as between wax and oil at reduced temperature and passing the resultant mixture through a chiller to precipitate wax therefrom, the improvement which comprises the addition to said solvent, prior to said passing, of ethanol, in an amount less than about 0.8 per cent by weight of said solvent but sufficient to inhibit the formation of a hard, adherent ice on the inner surfaces of said chiller due to the freezing of water contained in the mixture under treatment.

11. In the method of dewaxing a petroleum hydrocarbon, comprising blending said hydrocarbon with a dewaxing solvent consisting of from about 25 to about 40 per cent of a low boiling aliphatic ketone, from about 12 to about 25 per cent toluol and from about 40 to about 60 per cent benzol, and passing the resultant mixture through a chiller to precipitate wax therefrom, the improvement which comprises the addition to said solvent, prior to said passing, of a compound selected from the group consisting of water-miscible, oil-immiscible alcohols and organic acids in an amount less than about 0.8 per cent by weight of said solvent but sufficient to inhibit the formation of a hard, adherent ice on

the inner surfaces of said chiller due to the freezing of water contained in the mixture under treatment.

12. A method of dewaxing a petroleum hydrocarbon comprising blending said hydrocarbon with a dewaxing solvent consisting of benzol, toluol, and a low boiling aliphatic ketone combined in such proportion that a selective action is exerted as between wax and oil at reduced temperature and having incorporated therein a minor proportion less than 0.8 per cent by weight of said solvent mixture of a compound selected from the group consisting of water-miscible, oil-immiscible alcohols and organic acids, chilling the resulting mixture to precipitate wax therefrom, and thereafter separating the wax-oil-solvent mixture into its components.

13. A method of dewaxing a petroleum hydrocarbon comprising blending said hydrocarbon with a dewaxing solvent consisting of from about 25 to about 40 per cent of methyl ethyl ketone, from about 12 to about 25 per cent toluol, and from about 40 to about 60 per cent benzol, and having incorporated therein from about 0.02 to about 0.8 per cent by weight of said solvent mixture of a compound selected from the group consisting of water-miscible, oil-immiscible alcohols and organic acids, chilling the resulting mixture to precipitate wax therefrom and thereafter separating the wax-oil-solvent mixture into its components.

14. A dewaxing solvent comprising an oil solvent mixture of benzol and toluol and a wax anti-solvent consisting of a low boiling aliphatic ketone combined in such proportion that a selective solvent action is exerted as between wax and oil at reduced temperature and having incorporated therein a minor proportion of a compound selected from the group consisting of water-miscible, oil-immiscible alcohols and organic acids in an amount less than about 0.8 per cent by weight of said solvent but sufficient to inhibit hard, adherent ice formation during the dewaxing operation.
